Specification of Letters Patent.

Patented Mar. 16, 1915.

Application filed July 31, 1913. Serial No. 782,328.

To all whom it may concern:

Be it known that we, JAMES D. REIFSNYDER and GEORGE H. FATH, citizens of the United States, residing in Philadelphia and State 5 of Pennsylvania, have invented new and useful Improvements in Machines for Forming Sealed Wrapped Packages, of which the following is a specification.

This invention relates to machines for applying wrappers to packages for the purpose of forming what are known as "sealed wrapped packages", and is an improvement on that type of box covering machines set forth in Letters Patent granted to Philip S. 15 Smith, No. 691,329, dated January 14, 1902, and No. 778,805, dated December 27, 1904, and is an adaptation of machines of this class for the special purpose set forth.

The object of this invention is to provide 20 a machine for folding and sealing a wrapper around packaged materials especially such materials as are packed in boxes.

The package and the cover coated with an adhesive and applied to one wall of the 25 package are fed into the machine and, passing therethrough, the wrapper is first folded and sealed against the four vertical sides of the package, after which the projecting upstanding ends of said wrapper are turned over and secured to the remaining side of 30 the package, which in the case of a box is preferably the bottom, said turned over ends sealing the cover to the box and closing the space between the cover and box against entrance of foreign matter. The ends of the 35 wrapper secured to the bottom of the box do not cover the entire bottom, but extend thereover only sufficiently far to secure a tight seal.

An important feature of the invention 40 resides in the presser block or plunger by means of which the package is pushed through the folding mechanism. In the present machine it is necessary to have a 45 presser block of the same area as the package to be covered in order that the final turned over ends of the wrapper may be pressed against the upper surface of the package in order to secure a perfect adhesion of these ends to the package. It is also 50 necessary to have a presser block of less area than the package for the purpose of

holding the package in position while the projecting ends of the wrapper are being folded over on the upper side or in the present instance the bottom of the package, without contacting with the presser block. To accomplish these several results, the plunger or presser block is made in two parts, the smaller of which is adapted to be 60 seated in a recess or depression in the center of the larger block, their lower faces when so seated being in a common plane. The smaller presser block is moved positively throughout its range of movement and remains in contact with the package until ready for ejection from the machine. The larger presser block is connected yieldingly to the smaller presser block and is moved thereby simultaneously a certain distance, 70 after which it pauses for a predetermined time while the ends of the wrapper are being folded over upon the package, and then completes its movement, pressing said ends tightly against the upper surface of said 75 package.

Another important feature of the invention is a gage for positioning packages fed to the machine absolutely in line with the presser blocks or plungers, said gage being 80 movable with the plungers through a portion of their travel, or until the package has been securely gripped between the plungers and a depressible platen pressing respectively against the upper and lower faces of 85 the package.

A further feature of the invention is directed to a mechanism for removing packages from the machine after the covering operation has been completed. This mechanism is in the nature of a slowly moving pusher, positively actuated at the completion of each wrapping operation, and, after ejecting the package, is automatically returned by a quick movement to normal position before the next wrapping operation takes place.

With these and other objects in view the invention consists of a novel combination and arrangement of parts hereinafter described and illustrated in the accompanying drawings, in which—

Figure 1 is a side elevation of the machine from the front, portions being shown in

section to more clearly illustrate the invention. Fig. 2 is an end elevation partly in section as seen from the left of Fig. 1. Fig. 3 is a rear elevation of the upper portion of the machine, illustrating more clearly certain features of the invention. Fig. 3^a is a detail view in plan showing how the tuck-in fingers fold the projecting ends of the wrapper over the upper side of the package. Figs. 4 and 5 are views similar to Fig. 3, showing the parts there illustrated in different positions. Fig. 6 is a horizontal sectional view on the line 6—6 Fig. 5. Fig. 7 is a plan view of the wrapper blank. Figs. 8 to 13 are detail views of portions of the wrapper mechanism showing by progressive stages the manner in which a wrapper is folded and secured about a package. Fig. 14 is a perspective view of a sealed wrapped package. Fig. 15 is a detail sectional view of a portion of the wrapper folding mechanism. Fig. 16 is an elevation partly in section of the package ejecting mechanism. Fig. 17 is a plan view partly in section of the same mechanism.

Similar reference characters are used throughout all the figures to indicate like parts.

Referring first to Fig. 7, A is the wrapper as a whole made substantially of the form shown, on the central part *a* of which the package is placed after the upper surface of the wrapper has been completely covered with an adhesive. *a*¹, *a*⁴ are flaps projecting from opposite sides of the part *a*, of which the flaps *a*¹ are turned up by the first folding operation against corresponding sides of the package in which position side laps *a*² thereon will project beyond the other sides of the package and end laps *a*³ above the upper surface of the same. The side laps *a*² are next folded around the corners of the package against the sides thereof, after which the flaps *a*⁴ are folded against said sides and cover the end laps *a*³. From the flaps *a*⁴ end laps *a*⁵ project upwardly above the package, and in connection with the end laps *a*³, are folded over the upper side of said package to complete the wrapping and sealing thereof.

Mounted upon legs 20 which rise from the floor is a table 21, having an opening 22 in its center, through which projects the wrapper folding mechanism, and also, through which the package and the wrapper therefor are carried, during the course of the wrapping operation. Rising from the top of the table at the right side thereof is a vertical standard 23 from which an arm or bracket 24 projects toward the center line of the machine. Secured to said arm or bracket is an upright plate 25 provided on its front with two vertical guides 26 between which is mounted a slide 27, on

the lower end of which is fixed a pusher block or plunger 28 movable in a vertical line through the opening 22 in the table 21 by means of a counterbalanced lever 29 fulcrumed at 30 on an arm 31 projecting out from the standard 23. The free end of the lever 29 is pivoted to a link 32, adjustable in said link by a thumb screw 33. A pin 34 pivotally connects the upper end of the link to the slide 27. The vibration of the lever 29 on its fulcrum 30 reciprocates the slide 27 in its guides, thereby raising and lowering the pusher block or plunger 28.

A short distance below the table 21 is a plate 35 secured to the legs 20. Bolted to this plate are bearings 36 in which revolves a shaft 37, driven by a belt pulley 28 or other means, carrying a worm 39 fixed thereon. In rear of the worm 39 and driven thereby is a worm wheel 40 keyed on the lower end of an upright shaft 41 stepped in a bearing supported on the plate 35, said shaft extending vertically behind the standard 23 and above the same and turning in suitable bearings on the standard. On the upper end of the shaft 41 is a drum 42 in the periphery of which are two cam grooves 43, 44, that extend entirely around said drum, the lower cam 43 actuating the lever 29 by means of a stud or roller 45 carried by said lever.

On the lateral sides of the slide 27 at the bottom are lugs 46, in each of which is slidably mounted a rod 47, said rod extending vertically through suitable openings in the plate 35 to a suitable point above said plate 100 where they are connected by a cross head 48. The lower ends of the rods 47 are joined together by a plate 49 to which is removably connected a second pusher block or plunger 50 larger than the pusher block 28 and provided with a recess or depression 51 in its under side into which said pusher block 28 enters, and when so entered the under surfaces of the two pusher blocks lie in the same plane, as clearly shown in Figs. 1, 2 110 and 8 of the drawings. The pusher blocks 28 and 50 are made to be easily removable from the parts by which they are carried for the reason that the machine being adapted to operate on packages of different sizes 115 the blocks must be changed to suit the packages, block 50 having the same dimensions as the upper surface of the package, while block 28 is somewhat smaller in each dimension. Movement is imparted to the larger 120 pusher block 50 from the slide 27, by means of a resilient or yielding connection therebetween, which in the present instance is in the form of a coiled spring 52 connected at one end to a pin 53 projecting from said 125 slide 27, and at the other end to a pin 54 secured in the cross head 48 connecting the rods 47 at their upper ends.

Rotation of the cam drum 42 in the direction indicated by the arrow will cause the lever 29 to swing downwardly and move the slide 27 and the pusher block or plunger 28 thereon through the table 21. The larger pusher block or plunger 50 will move simultaneously therewith because of the connection 52 between the parts, until at a certain point in the movement of said plungers, the 10 larger plunger 50 will be temporarily arrested but the smaller plunger 28 will continue its movement until it has reached its lowest limit, to be followed later by the plunger 50. The two will then be returned 15 together to their uppermost position indicated in Fig. 1.

Slidable vertically in ears 55 projecting laterally from the right and left sides of the plate 25 are rods 56 connected at their upper 20 ends by a plate 57 which extends behind the slide 27 at a point between the top of the plate 25 and the cross head 48. The lower ends of the rods 56 are secured in the end of a U-shaped frame or bar 58 that curves rearwardly behind the rods 47, and the sliding stem 27 in order to clear the same, said frame or bar being connected by means of a link 59 to one end of a lever 60 pivotally mounted on the arm or bracket 24 intermediate its 25 ends and having at its opposite end a pin or roller 61 extending into the upper cam groove 44 on the drum 42. The lever 60 is rocked in a vertical direction when the cam drum 42 rotates, and through the link 59 raises and lowers the frame or bar 58. Near 30 the end of the lever 60 to which the link 59 is connected there projects a plate 62 in position to be struck by a downwardly extending adjustable pin 63 on the rear of the 35 cross head 48. The sequence of operations 40 of the parts described is such that when the plungers 28 and 50 in their descent have reached the predetermined point heretofore mentioned, the lower end of the pin 63 will 45 contact with the plate 62, thus preventing further descent of the plunger 50. At the proper time, however, the lever 60 is further depressed by the cam groove 44 and releases the pin 63, permitting the plunger 50 under 50 its own weight and the resiliency of spring 52 to finish its travel with a quick sudden movement for a purpose hereinafter set forth.

Fixed in the ends of the U-shaped frame or bar 58 and projecting to the right and left thereof in a horizontal direction and preferably in line, are two arms 64 upon each of which is adjustably mounted a collar 65 which may be moved longitudinally on said arm. Each collar 65 supports a finger 66, adjustable in a direction at right angles to the axis of the arms 64. On each finger at its rear end is a downwardly projecting angle shaped gage plate 67, which in the

normal position of the parts shown in Fig. 65 1, projects below the under surfaces of the plungers 28 and 50. These gage plates lie close to the rear corners of the pusher block or plunger 50, as shown in Fig. 6, and serve as a guide to position the box or package B 70 that is to be wrapped, relatively to the plungers when inserted in the machine.

Secured to the plate 35 which sustains the bearings for the worm shaft 37 is a support 68 in a vertical line below center of the 75 plungers or pusher blocks 28 and 50. A hollow bearing 69 projects upwardly from the support 68 in which bearing is mounted to slide in a vertical direction a hollow stem 70 on the upper end of which is secured a 80 platen 71 that serves as a support for the wrapper and the article to be wrapped during its passage through the wrapping mechanism. The platen is held above the plane of the table 21 by yielding pressure, in the 85 present instance a spiral spring 72 within the hollow stem 70 serves the purpose. When the plungers 28 and 50 and the frame 58 with the gage plates or fingers 67 descend with the wrapper and the article to be 90 wrapped, said article and wrapper engage the platen, and are held by and between said platen and the plungers during their progress through the folding mechanism, the spring 72 returning the platen and the 95 wrapped package to initial position after the wrapping operation has been completed.

The folding mechanism employed in this machine is in the main, substantially the same as that shown in the hereinbefore mentioned 100 patents granted to Philip S. Smith, and therefore, will be referred to here only in general terms.

On the top of the table 21 at the front and rear thereof, are guides 73 in which are 105 held plates or slides 74 adjustable to and from the center of the opening 22 in the table, said plates being held in adjusted position by set screws 75. The inner end of each plate 74 supports a roller 76, the ends 110 of which are mounted in bearings on the ends of arms 77 projecting upwardly from the plates 74. Also mounted on each arm 77 is a brush 78 above the roller 76 and substantially as long as said roller. Depending 115 from each plate 74 below the arm 77 is a bracket 79 provided with bearings which support a sliding frame 80, the inner end 120 of which frame has fixed thereon a bar 81 extending at right angles to the line of movement of said frame. On each bar 81 are two sleeves 82 on each of which is mounted a yielding side lap tuck-in finger 83. Each frame 80 with its two tuck-in fingers 83 is moved toward and away from the center of the machine by means of a three-armed lever 84 pivoted on a bracket 125 depending from the under side of the table

21 at its rear, and actuated by a cam groove 85 in a drum 86 fixed on the vertical shaft 41 that carries the drum 42. One of the arms 84^a is provided with a pin or roller engaging the cam groove 85, the other arms 84^b are connected by links 86^a with downwardly projecting arms 87 on cross shafts 88 one at the front and the other at the rear of the machine. An upwardly extending arm 89 on each shaft is connected by a link 90 one to the frame 80 at the front of the machine, and the other to the like frame at the rear of the machine. When the three-armed lever 84 is rocked, the frames 80 moves simultaneously to and from the center of the machine, and movable with each frame are the two side lap tuck-in fingers 83 mounted thereon.

On the right and left sides of the table 21 are plates 91 mounted in guides 92 in a manner similar to the plates 74, and carrying at their inner ends rollers 93, in a plane below the rollers 76 and at right angles to said rollers. Depending from the inner ends 25 of the plates 91 are brackets 94 similar to the brackets 79 but shorter. In each bracket 79 and 94 is mounted a horizontal sliding frame 95 to the inner end of which is fixed horizontal end-tuck-in fingers 96, the four 30 fingers lying in the same horizontal plane. Just below each frame 95 is a second horizontal sliding frame 97 each supporting on its inner end a presser block 98 from the exterior side of which projects a lug 99. 35 Mounted to rock in each bracket 79, 94 adjacent the lug 99 is a rocking cam 100 to which is fixed a short arm 101 by means of which said cam is actuated to advance the frame 97 with the presser blocks 98, and 40 through the medium of a link 102 pivoted to said arm and to the adjacent horizontal sliding frame 95, the end-tuck-in finger 96 connected to said sliding frame is advanced and retracted. Movement is imparted to 45 all the arms 101 to simultaneously advance the presser blocks 98, and the end-tuck-in fingers 96 by means of a sleeve 103 movable vertically on the bearing 69, said sleeve having four radially projecting arms 104 extending horizontally beneath the brackets 79, 94. On each each arm is an adjustable collar 105, from the top of which projects a pin 106 slideable through the bottom of the superjacent bracket. The upper end of 55 each of said pins 106 is connected by a link 107 with one of the short arms 101. Movement is imparted to the sleeve 103 by a cam groove 108 in the drum 86 actuating one end of a rocking lever 109 pivoted intermediate its ends upon an arm 110 extending from the bearing support 68, the other end of said lever being connected by a link 111 with the sleeve 103.

In the operation of the machine, the worm 59 is rotated continuously and through its

connection to the worm wheel 40 imparts continuous rotation to the vertical shaft 41 and the cam drums 42 and 86 thereon. At each rotation of the drums, when they arrive at the position shown in Fig. 1, a package B, which in the present instance is a box made of paper board filled with merchandise, and closed with a cover that projects over the box and extends to the bottom thereof. This box with its bottom uppermost 70 and a blank A adhering to the top of the cover is placed by an attendant against the under side of plungers 28, 50, and against the gage plates 67, which latter exactly position the box relatively to the plungers. As thus placed the flaps α^1 , α^4 , of the wrapper project laterally from the box as shown in Figs. 1, 2 and 8. Rotation of the cam drum 42 now causes the levers 29 and 60 to swing downwardly, simultaneously depressing the plungers and the gage fingers, the latter maintaining the box in position against said plungers during its passage to the platen 71. As soon as the box and the wrapper have reached or nearly reached the platen, the gage fingers 67 will pause, the plungers however continue their downward movement and press the box and wrapper against the platen to hold them securely in position against movement during their passage 95 through the wrapping mechanism. The approach of a box and its wrapper to the platen brings the two flaps α^1 of the wrapper into contact with the brushes 78, which turn up said flaps against corresponding sides of 100 the box. The plungers, box, wrapper, and platen now move downwardly together, the flaps all previously turned up by the brushes are by the rollers 76 pressed against the sides of said box into close contact therewith to cause the adhesion of said flaps, see Fig. 9. As soon as the box and wrapper have passed below the rollers 76 the downward movement is arrested momentarily, during which pause the sliding frames 80 105 are moved inwardly with their tuck-in fingers 83 to fold the side laps α^2 against the uncovered sides of the box, as in Figs. 3 and 10. Upon withdrawal of the frames 80, the downward movement of the box continues. The two flaps α^4 now encounter the rollers 93, by means of which said flaps are turned up against the remaining vertical sides of 110 the box and over the turned-in side laps α^2 , see Fig. 11. Passing the rollers 93 the plunger, partly wrapped box and platen now reach their lowest position, see dotted lines Fig. 1. Here the box is gripped by the presser blocks 90 which advance simultaneously toward the box and, pressing on the four sides the full width thereof from the upper surface or bottom of the box a greater or lesser distance down therefrom, insure a firm adhesion of the wrapper flaps to the box walls. After passing the lower rollers 93 115

120

125

130

but before arriving at the lowermost position the downward movement of the plunger 50 is arrested, the smaller plunger 28 however, continues to push the box and platen down, the plunger holding the box on the platen against the tension of the spring 72. The stoppage of the plunger 20 is for an instant only and is brought about by the lever 60 which has previously moved upward a predetermined distance and there held during the downward movement of the plunger. At the proper time, the pin 63 on the cross head 48 encounters the plate 62 on said lever 60 and prevents further movement of the plunger 50 so long as the lever 60 continues in a fixed position, see Fig. 4. The stoppage of the plunger 50 is to permit the end laps a^3 , a^5 of the wrapper to be folded over the upper surface or bottom of the box B. This folding is accomplished by means of the end-tuck-in fingers 96, all four of which move inwardly at the same time when the sleeve 103 is elevated by the cam drum 86 and lever 109. When said sleeve is lifted it raises the pins 106, and through the connections heretofore described, slide the frames 95 carrying the tuck-in fingers 96 and the frames 97 with the presser blocks 98, toward the box, turning the end flaps thereover and gripping the box. For the purpose of insuring the proper folding of the end laps a^3 , a^5 , it is desirable that two of them, as a^5 , be turned before the other two a^3 , so that the latter may overlie the former as in Fig. 14. This will prevent interference of the laps and secure a smooth tight sealing at all times. To cause the earlier folding of two of said laps the tuck-in fingers 96 which operate thereon may be made wider so as to engage said laps sooner, or the short arms 101 by which they are advanced may have a different leverage in order to advance earlier. After the tuck-in fingers have turned the end flaps a^3 , a^5 , over the upper surface or bottom of the box, see Fig. 12, they stop for an instant during which arrest the lever 60 again descends, thus releasing the pin 63 and the plunger 50, which latter through its weight and the tension of spring 52 drops upon the fingers 96, see Fig. 13, after which said fingers withdraw, permitting the plunger 50 to descend upon the end laps and press them against the upper surface of the box, sealing them tightly thereto and covering the space between the box and the edge of its closure. The presser blocks now release the box, the plungers are raised by the upward movement of lever 29, and the seal wrapped box is lifted by the plunger 50 through the tension of the spring 72 into position to be immediately discharged onto a run-way 112.

The wrapped packages may be removed from the platen 71 manually, or by a pusher 113 operated automatically by the vertical

shaft 41 at each rotation of said shaft. The pusher comprises a head 114 adapted to engage one side of the sealed wrapped package and push the same from the platen onto the run-way 112, said head being secured on the end of a horizontal rod 115 mounted to slide in a bearing 116 on the standard 23. On one side of the rod 115 is a rack 117 with which engages a gear wheel 118 turning on a short upright shaft 119 fixed at its lower end in a bracket, and surrounded by a coiled spring 120, one end of which is attached to the shaft support and the other end to a pinion 121 rotatable with the gear wheel 118. The pinion 121 is driven by a gear wheel 122, on one side of which is a pinion 123 with which a short toothed segment 124 mounted on the vertical shaft 41 engages at each rotation of said shaft. The number of teeth in the segment 124 is limited and engage the pinion 123 for a short period only during the revolution of the shaft 41. The engagement, however, is of sufficient duration to cause the gearing 122, 121, and 118, to move the plunger the required distance to discharge the package from the platen and wind up the spring 120, which as soon as the segment 124, in its rotation becomes disengaged from the pinion 123, reacts and returns the plunger head 114 to its inactive position, the shock of the quick return being prevented by a dash pot 125 into which the head 114 enters. In order that the pinion 123 may always be in position for the segment 124 to engage therewith without the respective teeth clashing, a positive stop is provided to insure the return of the plunger always to the same position. This stop is in the form of a pawl 126 pivoted to a fixed part of the frame and held by a spring against the plunger rod 115, a tooth 127 on said pawl engaging a notch 128 in the rod when the pusher head 114 has been retracted by the spring 120 into its rearmost position.

The pusher head moves slowly for the purpose of ejecting the sealed wrapped package, as distinguished from known types of spring impelled or shooting plungers, such movement being desirable because the box or other envelop is a filled box and has more or less weight, depending on the nature of its contents, and therefore the inertia of this weighted package must be overcome by a comparatively slow movement of the ejector, otherwise the latter if moved rapidly is liable to break through the wall of the package and spoil the same. The return movement of the pusher head may be as rapid as desired and for this reason the spring 120 is provided as a simple, efficient, and rapid motor for retracting the pusher.

The plungers 28 and 50 together have three functions in the operation of the machine, the first of which is to clamp the

6
 package and wrapper upon the platen and hold it thereon during its passage through the wrapper applying mechanism; the second is to push the package and the platen through said mechanism, and the third is to assist certain devices to fold and seal the end laps of the wrapper over the upper surface of the package, the last function being performed by the plunger 50 while the plunger 28 maintains the package in position. The dimensions of the former plunger are substantially the same as the upper surface of the package so as to bear upon the inturned laps of the wrapper, while the plunger 28 though sufficiently large to bear upon said upper surface of the package, and hold the same stationary against the tension of the spring 72 without breaking through the package, during the separation of the plungers, is small to permit the end laps of the wrapper being turned in and sealed without coming into contact with said plunger.

What we claim is:—

25 1. In a machine for forming a sealed wrapped package, the combination with wrapper applying instrumentalities for affixing an adhesively coated wrapper to all the walls of the package save one, leaving the 30 marginal edges of said wrapper projecting above the plane of the uncovered wall, of means for carrying the package and its wrapper through said wrapper applying instrumentalities including two plungers, 35 means for holding one of said plungers withdrawn, means for holding the other plunger against the package, means for tucking in said projecting marginal edges and means for advancing the withdrawn 40 plunger to press and seal said marginal edges against the package.

2. In a machine for forming a sealed wrapped package, the combination with wrapper folding and affixing instrumentalities for applying an adhesively coated wrapper to all the walls of a package save one, leaving the marginal edges of said wrapper projecting above the plane of the said uncovered wall, said folding instrumentalities including tuck-in devices for turning the 45 said projecting marginal edges of the wrapper over the uncovered wall of the package, of a package supporting platen and two co-operating plungers between which opposite 50 walls of the package and its wrapper are supported and carried through the folding instrumentalities, means for withdrawing one of the said plungers when said tuck-in devices are operating, and means for advancing the withdrawn plunger after said 55 tuck-in devices have operated to press and seal the package.

3. In a machine for forming a sealed wrapped package, the combination with wrapper folding and affixing instrumentalities

ties for applying an adhesively coated wrapper to all the walls of the package save one, leaving the marginal edges of said wrapper upstanding above the plane of said uncovered wall, said folding instrumentalities including devices for turning the said upstanding marginal edges of the wrapper over the surrounding edges of the uncovered wall of the package, of a package supporting platen and a co-operating two-part plunger between 70 which platen and plunger opposed walls of the package and its applied wrapper are supported and carried through the said folding instrumentalities, the lower surface of one of said plunger parts having substantially the same dimensions as, and the like 75 surface of the other plunger part being smaller than, the upper surface of the package, and means for causing the plunger part of greater dimensions to press upon and 80 affix the inturned marginal edges of the wrapper to the uncovered wall of the package while the latter is being held between the platen and other plunger part.

4. In a machine for forming sealed wrapped packages, the combination with wrapper applying instrumentalities, and a spring-pressed package supporting platen, of a two-part plunger movable as a unit toward said platen to grasp the top and bottom of a 90 package and an adhesively coated wrapper therebetween and carry them through the wrapper applying instrumentalities, the lower surface of one of said plunger parts having substantially the same dimensions as, 95 and the like surface of the other plunger part being smaller than, the upper surface of the package, said platen yieldingly supporting the package and co-operating with one of said plunger parts to press and seal 100 the folded package.

5. In a machine for forming sealed wrapped packages, the combination with wrapper applying instrumentalities, and a package supporting platen maintained in elevated 110 position by a yielding pressure, of a two-part plunger movable as a unit toward said platen to grasp the top and bottom of a package and an adhesively coated wrapper therebetween and carry them through the 115 wrapper applying instrumentalities, the lower surface of one of said plunger parts having substantially the same dimensions as, and the like surface of the other plunger part being smaller than, the upper surface 120 of the package and lying wholly within the margin of the larger plunger, said platen yieldingly supporting the package and co-operating with one of said plunger parts to press and seal the folded package.

6. In a machine for forming sealed wrapped packages, the combination with wrapper applying instrumentalities, and a spring-pressed package supporting platen, of a two-part plunger movable as a unit toward said 125

- platens to grasp the top and bottom of a package and an adhesively coated wrapper therebetween and carry them through said wrapper applying instrumentalities, the underside of one of said plunger parts having substantially the same dimensions as the upper surface of the package and a recess in the center thereof, the other plunger part being smaller and adapted to enter entirely within said recess, said platen yieldingly supporting the package and coöperating with one of said plunger parts to press and seal the folded package.
7. In a machine for forming sealed wrapped packages, the combination with wrapper applying instrumentalities, and a package supporting platen, of a two-part plunger movable as a unit toward said platen to grasp the bottom and top of a package and an adhesively coated wrapper therebetween and carry them through the wrapper applying instrumentalities, the active face of one of said plunger parts being of substantially the same size as the upper surface of the package, the other plunger part being smaller and adapted to nest centrally within a recess in the larger part, means for reciprocating the smaller plunger part, and a resilient connection between the two parts.
- 30 8. In a machine for forming sealed wrapped packages, the combination with wrapper applying instrumentalities, and a package supporting platen, of a two-part plunger movable as a unit toward said platen to grasp the bottom and top of a package and wrapper therebetween and carry them through the wrapper applying instrumentalities, the active face of one of said plunger parts being of substantially the same size as the upper surface of the package, the other plunger part being smaller and adapted to nest centrally within a recess in the larger part, means for reciprocating the smaller plunger part, a yielding connection between the two parts, and means for temporarily interrupting the advance of the larger plunger part near the end of its stroke.
9. In a machine for forming sealed wrapped packages, the combination with wrapper applying instrumentalities, and a package supporting platen, of a plunger movable toward said platen to grasp the top and bottom of a package and wrapper therebetween to carry them through said wrapper applying instrumentalities, a gage for positioning the package relatively to the plunger and guiding it to the platen, and means for moving said gage toward the platen and in the same direction as the plunger when the plunger descends.
10. In a machine for forming sealed wrapped packages, the combination with wrapper applying instrumentalities, and a package supporting platen, of a plunger
- having substantially the same area as the package movable toward said platen to grasp the top and bottom of a package and wrapper therebetween and carry them through said wrapper applying instrumentalities, and a gage for positioning the package relatively to the plunger movable simultaneously in the same direction with but independently of the plunger for guiding said package to the platen.
11. In a machine for forming sealed wrapped packages, the combination with wrapper applying instrumentalities, and a package supporting platen, of a removable plunger having substantially the same area as the package movable toward said platen to grasp the top and bottom of a package and an adhesively coated wrapper therebetween and carry them through said wrapper applying instrumentalities, and a gage for engaging one or more corners of said package for positioning the same relatively to the plunger and adjustable to the size of said package, and means for moving said gage simultaneously with but independently of the plunger and in the same direction with the plunger to guide said package to the platen.
12. In a machine for forming sealed wrapped packages, the combination with wrapper applying instrumentalities, and a package supporting platen, of a plunger having substantially the same area as the package movable toward said platen to grasp the top and bottom of a package and an adhesively coated wrapper therebetween and carry them through said wrapper applying instrumentalities, and a gage for positioning said package relatively to the plunger comprising angle plates or fingers closely embracing two corners of said plunger and projecting below the same adjustably mounted on a movable support, and means for moving said gage fingers simultaneously with but independently of the plunger.
13. In a machine of the class described, a pusher for moving away the finished article, a pinion, means actuated by said pinion to advance said pusher, and a shaft arranged to be rotated continuously and having a segment adapted to engage said pinion during a portion of the revolution of said shaft to actuate said pusher periodically.
14. In a machine of the class described, a pusher for moving away the finished article, a pinion, means actuated by said pinion to advance said pusher, and a shaft arranged to be rotated continuously and having a segment adapted to engage said pinion during a portion of the revolution of said shaft to actuate said pusher periodically, and a spring for returning said pusher after its actuation by said segment.
15. In a machine of the class described,

in combination, a pusher for moving away the finished article including a rack, a gear wheel meshing with said rack, a pinion arranged to rotate said gear wheel, means for periodically rotating said pinion and a spiral spring for giving said gear wheel a return movement to return the pusher after a rotation of said pinion.

In testimony whereof we have hereunto set our hands in presence of two subscribing witnesses.

JAMES D. REIFSNYDER.
GEORGE H. FATH.
